5 Claims**ABSTRACT OF THE DISCLOSURE**

A portable diving platform including a foldable step ladder having hinged sections that are angularly spread to define a standing support, a platform mounted on the sections for supporting a diver, and an anchor means interconnecting the bases of the two sections and being constructed for receiving water therein to act as a ballast for holding the platform from movement when it is submerged in water.

The present invention relates to improvements in portable diving platforms and more particularly to a partially submergible diving platform and ladder.

Heretofore, where it has been desired to provide a diving platform, it has been necessary for the same to be positively anchored as by use of pilings or stakes, or other heavy weights were required. This is objectionable for the reason that a portable diving platform must be lightweight and easy to install.

Accordingly, it is a primary object of the present invention to provide an improved portable diving platform which requires no positive anchoring means, such as pilings or stakes.

Another object of the present invention is to provide an improved portable diving platform which is lightweight and simple to install and obviates the need for weights.

Still another object of the present invention is to provide an improved portable diving platform which is compact for transporting and yet stable and sturdy when installed and ready for use.

A further object of the present invention is to provide an improved portable diving platform which utilizes inexpensive material and is easy to manufacture and assemble.

Various other objects and advantages will become apparent from the detailed description to follow.

In the drawings:

FIGURE 1 is a perspective view of a portable diving platform in accordance with the present invention mounted ready for use;

FIGURE 2 is a side elevational view thereof shown submerged in water.

Referring more particularly to the drawings wherein like numerals apply to like parts throughout, it will be seen that I have provided an improved portable diving platform 10 which includes a foldable step ladder 12 and an anchor means 14.

The foldable step ladder 12 is comprised of a pair of sections, first section 16 and second section 18. The first 16 includes a pair of side bars 20, 22 angulated at common ends as at 24, 26 and having platform 28 secured to the ends 24, 26 by rivets 30. A U-shaped bar 32 has a pair of side legs 31, 33 telescopically receiving the bars 20, 22 therein with the sleeves 34, 36 and set screws 38, 40 func-

2

tioning for adjustment purposes. The legs 31, 33 have hooks 42, 44, 46, 48 secured thereto for a purpose to be described.

A series of steps 50 straddle the bars 20, 22 and legs 31, 33 and are secured thereto in any desired fashion.

The second section 18 includes a pair of bars 52, 54 and another U-shaped bar 56 with hollow side legs 58, 60 telescopically adjustably receiving the bars 52, 54 therein. Hooks 62, 64 also are provided on each of the legs 58, 60. The upper ends of bars 52, 54 are pivoted to the platform, as at 66. Linkage at 68, 70 join the two sections and rigidly support the same in the relationship shown in full lines but the two sections can be folded when the linkage is folded as shown in dotted lines in FIGURE 2, as when it is desired to transport the entire platform.

The anchor means 14 comprises a box open at the top and formed by four side walls 72, 74, 76, 78 joined by a bottom wall 80, the depth of the box being approximately equal to the height to the first step. The corners of the box have straps 82, 84 attached thereto, as by stitching, and the straps have eyelets formed therein as at 86, 88 for engagement on the respective hooks. The entire box and straps are made of flexible waterproof fabric such as canvas.

Thus when mounted in position in water the anchor box is filled with water and when a diver leaves the platform 28, any tendency for the device to tip is substantially completely inhibited by reason of the resistance of the box to movement under water.

Accordingly, it is believed that I have provided an improved portable diving platform which fulfills the objects hereinbefore enumerated.

As this invention may be embodied in several forms without departing from the spirit or essential characteristics thereof, the present embodiment is therefore illustrative and not restrictive, since the scope of the invention is defined by the appended claims rather than by the description preceding them, and all changes that fall within the metes and bounds of the claims or that form their functional as well as conjointly cooperative equivalents, are therefore intended to be embraced by these claims.

I claim:

1. A portable diving platform comprising a foldable step ladder including first and second sections hingedly connected so as to be movable between two end positions in one of which end positions the two sections are folded together and in the other of which end positions the two sections are angularly spread for standing support thereof, said two sections being joined by a flat platform adapted to support a diver, and an anchor means interconnecting the bases of said two sections, said anchor means being constructed for receiving water therein and thereby acting as a ballast for holding said platform from movement when submerged in water.

2. A portable diving platform comprising a foldable step ladder including first and second sections hingedly connected so as to be movable between two end positions in one of which end positions the two sections are folded together and in the other of which end positions the two sections are angularly spread for standing support thereof, said two sections being joined by a flat platform adapted to support a diver, and an anchor means coupling the bases of said two sections and holding said platform from movement when submerged in water, said anchor means being defined by a flexible, collapsible box.

3. A portable diving platform according to claim 2 wherein said box includes side walls and a bottom wall formed of waterproof fabric, and anchor straps connecting said side walls with said two sections.

4. A portable diving platform according to claim 3 wherein said box is rectangular and of a size when expanded to extend substantially from one section to the other and being substantially as wide as said sections.

5. A portable diving platform according to claim 4 wherein said box is open at the top and has a depth substantially equal to the height between steps of said ladder.
